UNITED STATES PATENT OFFICE.

ELI W. F. McMILLAN, OF EVERETT, WASHINGTON.

GRATE FOR FURNACES.

1,262,221.

Specification of Letters Patent.

Patented Apr. 9, 1918.

Application filed January 5, 1916. Serial No. 70,545.

To all whom it may concern:

Be it known that I, ELI W. F. McMILLAN, a citizen of the United States, residing at Everett, in the county of Snohomish and 5 State of Washington, have invented a new and useful Improvement in Grates for Furnaces, of which the following is a specification.

This invention relates to improvements in 10 grates for furnaces, refuse burners and the like, and the object of this improvement is to provide a sectional grate of strong and simple construction that is so formed that ashes and clinkers or fuel can not settle 15 down as a blanket thereon and close the draft openings through the grate.

This invention consists in the novel form 20 of construction of a grate as will be more clearly described in the following specification, illustrated in the accompanying drawings and finally pointed out in the appended claim.

In the drawings Figure 1 is a view in 25 cross section of three sections of a grate embodying this invention; Fig. 2, is a view in longitudinal midsection of one section of the same; Fig. 3, is a view in perspective of one section of a modified form of the invention; and Fig. 4 is an enlarged view in 30 cross section of the form of grate shown in Fig. 3.

Referring to the several views throughout which like reference numerals indicate like parts, the numeral 5 indicates one section 35 of a grate which may be considered as built up of a base portion 6 and a top portion 7.

The top portion 7 is made up of two intersecting walls that form an apex or gable 40 upon which the fuel rests, and such walls are provided with longitudinal slots 9 through which air may pass to support combustion, the slots 9 preferably being narrower at the top than they are at the bottom and being formed at an angle to the 45 plane of the walls so that they are substantially vertical when the grate is set up.

The base 6 of each grate section 5 terminates at each end in a squared portion 10 50 that is adapted to rest upon a support (not shown) and the top portion 7 of each grate section is inclined outwardly from top to bottom, as indicated at 14 and is also provided with slots 9 through which air may 55 pass.

The side walls of the base portion 6 of

each section converge slightly toward the bottom of the section and are each provided with external spacing members 11 having vertical faces that coengage when two or 60 more sections 5 are placed side by side, thus causing a slot that converges slightly toward the top to be left between adjacent grate sections.

A bridge 12 may be placed in the center 65 of each grate bar if desired, and the slots 9 may be relatively short in length with transverse ribs 13 therebetween to strengthen the grate section.

When in use a plurality of the sections 5 70 are placed side by side within a furnace to form a grate which consists in a series of gables 8 upon which the fuel may rest with troughs between the adjacent gables, the grate when viewed in cross section as shown 75 in Fig. 1 presenting a serrated or saw-toothed appearance.

In Figs. 3 and 4 I have shown a grate section having the same general shape as the section 5 and consisting in a frame 15 having slots 16 in each end wherein bars 17 may be placed to extend lengthwise thereof and form a grating. The bars 17 are tapered toward the bottom edge thereof in order that the slots between such bars may converge slightly toward the top. This insures 85 that any clinker that is small enough to pass through the top of the slots between the bars 17 will not wedge between the bottoms of such bars and thus retard the draft. 90

The side walls of the frame 15 are provided with spacing members 18 similar to the spacing members 11 whereby a draft slot will be left in the bottom of the trough that is formed when several grate sections 95 are placed side by side.

It will be noted in Figs. 3 and 4 that the top of each of the bars 17 is flat and lies substantially in a horizontal plane instead of lying in the general inclined plane of the 100 top portion of the grate section. This makes it still more difficult for ashes, fuel and clinkers to settle down on the grate and shut off the draft.

If one or more of the bars 17 are broken 105 or burned out, they may readily be replaced without replacing the entire grate section.

The advantage of my form of grate in 110 operation resides in the fact that the clinkers, fuel and ashes as they settle thereon will rest upon the gables 8 and will be broken up thereby and fall through the

openings 9 or the spaces between the bars 17 as they slide down the angular walls of the top of the grate sections instead of forming a blanket on the grate that closes the draft as often occurs in an ordinary flat grate.

I have found by experiment that the use of this grate in refuse burners that are connected with lumber mills greatly increases 10 the efficiency of a burner and causes practically all of the refuse that is directed thereinto to be consumed without attention while where an ordinary flat grate is used a great amount of ashes and clinkers is formed, and 15 these ashes and clinkers, together with the unconsumed fuel, will settle down on the grate and shut off the draft in a short time.

Obviously my grate may be made in one

solid piece if desired, but for large grates it is found to be more practical to build the 20 grate in sections.

Having described my invention what I claim as new and desire to protect by Letters Patent, is:

A grate section, comprising a rectangular 25 base portion formed with spacing members, upwardly and inwardly extending side and end walls, intersecting one another to form gables, said walls being provided with vertical perforations.

Signed by me at Everett, Washington, this 27th day of December, 1915.

ELI W. F. McMILLAN.
